UNITED STATES PATENT OFFICE

EMMIT G. LATTA AND ADRIAN C. LATTA, OF FRIENDSHIP, NEW YORK.

VELOCIPED.

SPECIFICATION forming part of Letters Patent No. 322,113, dated July 14, 1885.

Application filed March 13, 1885. (No model.)

To all whom it may concern:

Be it known that we, EMMIT G. LATTA and ADRIAN C. LATTA, both of Friendship, in the county of Allegany and State of New York, 5 have invented new and useful Improvements in Velocipedes, of which the following is a specification.

This invention relates to the steering mechanism of velocipedes, and has for its object to 10 improve the means whereby the steering-head is connected with the perch; also, to improve the fastening whereby the handle-bars are attached to the steering-head, and, finally, to improve the means of attaching the handles 15 to the handle-bars.

Our invention consists, to these ends, of the improvements which will be hereinafter fully set forth, and pointed out in the claims.

In the accompanying drawings, Figure 1 is 20 a fragmentary sectional front elevation of the steering-head and handle-bars. Fig. 2 is a longitudinal vertical section of the steering-head. Figs. 3, 4, and 5 are cross-sections of the steering-head in lines $x\ x$, $y\ y$, and $z\ z$, Fig. 2, respectively. Fig. 6 is a sectional elevation showing a modified construction of the upper part of the steering-head. Fig. 7 is a cross-section of the handle in line $x\ x$, Fig. 1.

Like letters of reference refer to like parts 30 in the several figures.

A represents the steering-head; A', the perch, and A² the neck or front portion of the perch which enters the steering-head.

B represents the spindle, which is secured 35 in the front portion of the neck A², and provided with upper and lower centers, b b', on which the steering-head turns. The spindle B is provided with an external screw-thread, by means of which it is detachably secured 40 in a threaded vertical bore, c, formed in the front portion of the neck A². The centers b b' are arranged out of line with the threaded portion of the spindle B, as represented in Fig. 2, so that by giving the spindle B a half-turn in its socket the position of the perch 45 with reference to the steering head and fork can be changed. In the position of the parts represented in full lines in Fig. 2 the perch is brought close to the driving-wheel, being the 50 best position for riding on good roads. By giving the spindle a half-turn the perch assumes the position represented by dotted lines

in the same figure, in which the rear wheel is moved farther back and the rake of the front fork is increased, thereby bringing the rider 55 farther back from the center of the driving-wheel, in the position which is most desirable for rough or hilly roads.

The extent of variation or adjustment may be varied by supplying a number of spindles 60 having their centers out of line with the threaded portion to a greater or less extent, and a position of adjustment midway between the two adjustments afforded by a single spindle can be obtained by inserting a straight 65 spindle in which the centers are arranged in line with the threaded portion of the spindle. We prefer to secure the spindle in the neck by a screw-thread; but other modes of fastening may be employed without departing from the 70 spirit of our invention.

C is a set-screw arranged in the neck A and impinging against the spindle B, for further locking the spindle in position after it has been adjusted in the neck. By vertically 75 adjusting the spindle in the neck the latter may be raised on the spindle to give more room between the perch and wheel when riding on muddy roads; or, if desired, the perch may be lowered on the spindle, thus enabling 80 the machine to be adjusted for riders of different sizes, and for modifying the rake to some extent.

The spindle can be easily removed from the neck A and replaced by a new one when worn. 85

D represents the adjusting-screw or adjustable center bearing secured to the upper portion of the steering-head, and resting upon the upper center, b. The upper portion of the steering-head which surrounds the screw D is 90 split, as shown at d in Fig. 3, and clamped against the screw D by a tapering screw-nut, E, which surrounds the split portion of the steering-head. Upon screwing the nut E down on the steering-head the upper portion 95 of the latter is compressed, whereby the adjustable center bearing, D is firmly locked after having been adjusted. It is obvious that the steering-head may be provided with a number of slits, if desired. The upper end of 100 the screw-nut E is shaped to receive a wrench for turning the same.

F represents the dust-cap, secured to the upper end of the adjusting-screw D, and cov-

ering the same. The dust-cap must be removed to adjust the screw D. If desired, the dust-cap may be formed directly on the upper end of the nut E, as represented in Fig. 6. 5 The spindle may be extended nearly to the top of the steering-head, as represented in the same figure, whereby a very long spindle is supplied, while the adjusting-screw D perfectly supports the upper end of the spindle 10 against lateral movement, which prevents the steering-centers from wearing oval.

G represents the handle-bar lug formed at the front side of the steering-head A, and composed of two inclined tubular arms or 15 parts, g g, connected at their lower ends and projecting upwardly and outwardly from the middle of the steering-head, as represented in Fig. 1.

H H represent the handle-bars, seated with 20 their inner portions in the branches g g of the lug G, and having their inner ends overlapping each other and secured in the handle-bar lug by a fastening-screw, h. This construction of the handle-bar lug locates the seat or point 25 of attachment of the handle-bars to the steering-head farther down than is possible with the usual constructions, and permits the handle-bars to be made without a reversed curve, while allowing the necessary room for the legs 30 of the rider. The overlapping ends of the bars cause the latter to hold each other against turning in the lug and relieve the fastening-screw from all strains excepting strains which act lengthwise of the handle-bars. The handle-bar lug is attached to the steering-head 35 near the heavy portion of the head, and is therefore less liable to break, and as it is secured to the head near the middle of the spindle, the steering is somewhat improved. 40 The inclined position of the lug-branches enables the handle-bar to spring more readily when the machine falls over sidewise and strikes on the handle.

I represents the handle, made of the usual 45 pear shape, or any other suitable form, and i is the tang formed at the outer end of the handle-bar H, and supporting the handle.

J is a ferrule or socket, secured in the handle I, and having its inner portion, j, provided 50 with an internal screw-thread, which engages with an external thread on the outer portion of the tang i. The outer portion, j', of the ferrule J is somewhat larger in diameter than the inner part thereof, and connected 55 with the inner portion by a tapering portion, j².

K represents a locking screw-sleeve arranged in the outer portion of the ferrule J around the tang i, and provided at its inner 60 end with a tapering portion, which bears against the tapering portion j² of the ferrule. This screw-sleeve is preferably split, as represented at k in Fig. 7, to lock the handle tightly 65 on the tang upon screwing the sleeve K into the ferrule J. The latter is arranged on one side of the center line of the handle, as clearly shown in Figs. 1 and 7, so that upon loosen-

ing the handle on the tang and turning the handle the latter may be arranged to project or incline above or below the tang or forwardly or backwardly, as may be convenient. 70

It is obvious that the center line of the socket may be arranged on one side of the center line of the handle, or that it may intersect said center line; also, that the handle 75 may be provided, in addition to the inclined socket, with a socket arranged centrally in the handle, so that the handle may be secured to the handle-bar in the ordinary position, if desired. 80

We claim as our invention—

1. The combination, with the steering-head and neck, of a spindle removably secured in the neck and held therein against turning, substantially as set forth. 85

2. The combination, with the steering-head, of a neck provided with a screw-threaded socket and a screw-threaded spindle seated therein, substantially as set forth.

3. The combination, with the steering-head and neck, of a spindle made vertically adjustable in the neck, substantially as set forth. 90

4. The combination, with the steering-head and neck, of a reversible spindle seated in the neck and having its centers arranged 95 out of line with its seat, substantially as set forth.

5. The combination, with the steering-head and the neck provided with a screw-threaded socket, of a spindle provided with a screw-threaded portion engaging in said socket, and centers arranged out of line with said screw-threaded portion, substantially as set forth. 100

6. The combination, with the spindle and upper adjustable center bearing, of a split 105 steering-head having an external screw-thread, and a clamp-nut inclosing the split head, substantially as set forth.

7. The combination, with the spindle, of the screw-bearing D, the steering-head A, provided with an upper split portion, and a tapering screw-nut, E, substantially as set forth. 110

8. The combination, with the steering-head, of a handle-bar lug composed of two sockets arranged at an angle to each other, substantially 115 as set forth.

9. The combination, with the steering-head, of a V-shaped handle-bar lug arranged with its point downward in front of the steering-head, substantially as set forth. 120

10. The combination, with the steering-head, of a handle-bar lug composed of two sockets joined at their lower ends and projecting upwardly and outwardly from their junction, and handle-bars having their inclined inner 125 ends seated in said sockets, substantially as set forth.

11. The combination, with the steering-head, of a handle-bar lug composed of two sockets arranged at an angle to each other, and two 130 handle-bars seated in said sockets and having their inner ends in contact with each other, whereby the bars are held from turning, substantially as set forth.

12. The combination, with the steering-head A, of the lug G, composed of connected inclined sockets $g\ g$, handle-bars H, and fastening-screw h, substantially as set forth.
- 5 13. The combination, with the handle-bar, of a handle having its socket for the reception of the handle-bar arranged outside of its center line, substantially as set forth.
14. The combination, with the handle-bar, 10 of a handle adjustably secured to the bar, and having its socket for the reception of the handle-bar arranged outside of its center line, substantially as set forth.
15. The combination, with the handle-bar provided with a screw-threaded tang, i, of a handle, I, provided with a screw-threaded ferrule, J, having a tapering portion, j^2 , and a clamping-sleeve, K, substantially as set forth.

Witness our hands this 9th day of March, 1885.
